MEANS FOR TENSIONING METALLIC MATERIAL IN COLD REDUCING MILLS

Earl D. Spangler, Gary, Ind.

Application May 15, 1941, Serial No. 393,622

2 Claims. (Cl. 80—51)

This invention relates to the rolling of metal stock, and particularly to improved means for tensioning metallic material, such as elongated ferrous stock, steel strip, sheets, and the like while cold reducing the same.

In certain classes of mills, particularly cold reducing mills of the reversing type, provision is generally made for tensioning the stock being reduced in order to minimize the arcs of contact between the work rolls and the stock to provide for the uniform flat entry of the stock into the bite of the rolls and, in general, to bring about a more satisfactory rolling condition. In tandem mills, usually comprising three to five roll stands arranged in line, the difficulties of providing suitable means for tensioning strip being reduced through all of the stands are greatly increased to the point where tension is applied only partially, if applied at all.

At the present time there are many types of tensioning equipment in use, most of which are grouped into two general categories:

First, those which provide for the retardation of the pay-off reel so that the material is tensioned between the latter and the takeup reel through the roll pass; and

Second, those which, by means of clamps, shoes, or drags, resist the advancement of the stock into the roll pass to tension the same.

The first group of tensioning devices usually involves rather expensive, elaborate equipment which is not well suited to all cold strip mills, and is subject to the further limitation of being applicable only in the reduction of stock of sufficient length to be coiled, and capable of extending for a substantial part of the rolling operation from the pay-off to the takeup reel.

The second class of devices is, for the most part, applicable to any type of cold rolling mill in present day use, whether originally designed for tensioning or not, since the drags or clamps can be added to the existing equipment without much difficulty. These latter, however, have been subject to certain disadvantages, including the rapid wearing away of the clamp shoes, the necessity for frequent replacement, and the not infrequent uneven wearing away of such shoes or bearings, so as to pull and wrinkle the material entering the mill to a harmful degree. Another disadvantage of the latter class of tensioning devices lies in the fact that they are disposed directly in the line of the pass, obstructing the view of the operator and having such limited movement as to be in the way during threading up operations. Furthermore, for the most part, the

position of these devices away from the mill is sufficiently removed from the pass of the mill as to make their use in the rolling of the sheets, or other relatively short lengths of metal stock, impracticable.

5 A serious objection to both classes of tensioning devices as heretofore constructed arises from the fact that they must be disposed such a distance from the work rolls as to render the tensioning of substantial lengths of the trailing ends of coils of strip impossible nearing the conclusion of each rolling operation. Thus, the ends of strip extending from the tension device to the roll pass (usually a dozen feet or so) are rolled under different conditions (without benefit of tension) than the remainder of the strip, consequently requiring the scrapping of this amount of each coil due to departure from gage, surface defects, etc. In tandem mills where a speed differential between pay-off and takeup reels is relied upon to create the desired tension, a length of strip corresponding to the distance between these reels is produced at the end of each coil rolled which, in the larger mills, would equal nearly 100 feet of strip at the end of each coil that would have to be scrapped.

20 In the present invention, there is provided a tensioning means for cold reducing mills wherein all of the above named disadvantages have been eliminated, thereby providing an improved finished product.

Accordingly, it is one of the objects of the present invention to provide a tensioning means which may be readily applied to any of the ordinary types of mills now in use, which can be used not only for tensioning long lengths of stock, but which also may be used in the reduction of sheets, and other short lengths of stock while at the same time being in the way of the operator neither during the rolling operation nor during the threading up period.

45 It is another object of the invention to provide a tensioning means which is simple and inexpensive in its construction and, yet, a means which operates efficiently and effectively to maintain, under tension, those portions of strip or sheets being rolled that are engaged by the work rolls of a mill down to, and including, the trailing end extremities thereof.

50 Various other objects and advantages of this invention will become more apparent during the course of the following specification and will be particularly pointed out in the appended claims.

55 In the accompanying drawing there is shown,

for the purpose of illustration, one embodiment which my invention may assume in practice.

In the drawing:

Figure 1 is a vertical sectional view through a conventional 4-high cold reducing mill, which may be a single stand mill or representative of one of the stands of a tandem mill, showing the improved tensioning means of my invention incorporated therewith;

Figure 2 is a front elevation of the lower portion of the mill showing the tensioning means of the present invention.

Referring more particularly to the drawing, the improved tensioning means of my invention is shown incorporated with a 4-high cold reducing rolling mill which comprises generally a frame 2, a pair of oppositely disposed work rolls 3 and backing up rolls 4. The strip to be reduced is introduced between the work rolls 3 and delivered to a takeup reel 5 arranged on the delivery side of the mill in a manner well known to those skilled in the art. It will be understood that that portion of the strip S' on the delivery side of the mill is maintained under tension at all times by means of the takeup reel 5.

According to the present invention, there is arranged on a suitable support on the entry side of the mill and disposed preferably below the pass line of the strip therethrough, preferably a pair of angularly disposed fluid pressure cylinders 6 preferably operated by compressed air, with each having a piston 7 and piston rod 8 which extends from the upper end thereof. There is mounted on the outer ends of the piston rods 8 and extending therebetween a shoe or drag member 9 which is preferably constructed of wood, but may be constructed of any other suitable material, and which is adapted to be moved toward and away from the upper work roll 2 by the action of the fluid pressure cylinders 6. The cylinders 6 are actuated by a source of fluid pressure (not shown) which is adapted to be introduced from the source of supply through a pipe line 10, into and through the reversing valve 12 and through the pipes 13 into the cylinders, so as to either move the shoe upwardly into engagement with the strip and upper roll, or to move the shoe to a retracted position below the path of the strip, as shown in the broken lines of Figure 1. It will be understood that that portion of the strip S'' on the entry side of the mill is normally not under tension in the practice of the present invention and the strip will normally hang slack, as shown in the broken lines of Figure 1.

The tensioning means of my invention functions in the following manner. When threading up the mill, the valve 12 is actuated so that fluid pressure is introduced into the upper end of the cylinders 6 through the lines 13 whereby the piston rods 8, together with the shoe 9 carried thereby, are withdrawn away from the strip to a retracted position therebelow, as shown in the broken lines of Figure 1, with such position being below the path or pass line of the strip between the rolls 3 and through the mill so as to enable the operator to properly thread the material through the mill. After the mill has been threaded and operating conditions achieved with the leading end of the strip being wound on the takeup reel 5, so that the portion of the strip S' on the delivery side of the mill is under tension, the valve 9 is actuated so as to relieve the pressure at the upper end of the cylinders 6 and simultaneously to introduce fluid pressure into

the cylinders, at the opposite or lower ends thereof, so that the piston rods 8, together with the drag shoe 9 carried thereby will be moved upwardly against the bottom of the strip so as to move the same against the upper work roll 3, as shown in the full lines of Figure 1. It will be understood that sufficient pressure is introduced into the bottom of the cylinder 6 so that the strip is confined under substantial compressive force at point A between the shoe 9 and the upper work roll.

It will be understood that it is the purpose of the drag shoe 9 to impose a drag on that portion of the strip S' on the entry side of the mill which is approaching the mill in a slack condition. It will thus be seen that this places that portion of the strip between point A and point B, the bite of the work rolls 3, under tension and that tension is maintained between the bite of the rolls and across the span of the reduced strip S' to the takeup reel 5 which exerts a constant pull thereon. The portion of the strip between the points A and B is maintained under tension while the metallic material is passing continuously between the work rolls 3 due to the fact that the component of friction existing between the bottom surface of the strip and the drag shoe 9 is greater than the frictional component prevailing between the upper surface of the strip and the work roll 2, since the latter constitutes a metal-to-metal contact, while the former is a metal-to-fibre contact. That is to say, the coefficient of friction between wood and metal is greater than that between metal and metal where the two metal surfaces tend to move in unison in the same direction, while the fibre surface remains stationary relative to the moving metal surface of the strip. Therefore, a frictional drag is obtained at point A so as to place the strip under tension. The action of the drag member 9 is similar in effect to forcing a wedge between one surface of the strip in the bite of the rolls and one of the rolls itself.

Apart from the tensioning function performed by my device as described above, it will be seen that by the use thereof there is provided sufficient tension in the strip immediately before the same enters between the work rolls so as to prevent the strip from piling up or doubling over and resulting in socalled "pinchers" in the strip, which is objectionable in that such "pinchers" oftentimes damage the work rolls and consequently necessitate the replacement thereof. The drag shoe 9 of my invention will not only eliminate the occurrence of the above referred to "pinchers" but also possesses all of the advantages of a tensioning means for accomplishing the purposes for which such means are provided as hereinbefore set forth.

While in the present instance, the drag shoe 9 is shown positioned below the strip and cooperating with the upper work roll, it will be seen that the reverse of this arrangement could be adopted if desired, whereby the drag bar or shoe, together with its actuating mechanism would be mounted above the strip with the drag shoe then cooperating with the lower work roll.

It will be observed that because the tension afforded by the present invention is applied so close to the reducing zone of the work rolls (never exceeding a distance corresponding to the radius of the work rolls), it may be applied in the reduction of short lengths of material, such as individual sheets, as well as to relatively continuous lengths of stock similar to strip. In this re-

gard, it will be appreciated that the invention is applicable to single stand mills (one of my devices being used at each side of such a mill if it be a reversing mill) and to tandem mills, in which case, the invention would preferably be applied to each of the stands thereof. It will also be apparent that whether the tensioning apparatus is disposed above or below the pass line of the mill, it will have sufficient operating range and such simplicity of construction as to be withdrawable completely from the path of travel of the strip and from the pass line of the mill, so as to be out of the line of vision of the operator, and to afford plenty of room in which to work.

It will also be understood that any suitable means for forcefully propelling and holding the shoe against the strip may be utilized without departing from the spirit of the invention, as, for instance, reverse screw jacks could be substituted for the fluid pressure means disclosed herein for illustrative purposes only. One advantage of the fluid pressure operating means for controlling the movement of the shoe, particularly where the fluid pressure is supplied from a common source, is that it has a tendency to equalize and, thus, to cause the shoe to bear upon the strip uniformly across the width of the latter. Where screw jacks, or other mechanical means, are provided, the shoe may be pivoted or swiveled to the actuating rods 6 (which might be only one in number, disposed centrally of the shoe) so that the latter may have some flexibility of movement in accommodating itself to the placement of the strip and the mill rolls.

While I have shown and described one specific embodiment of my invention, it will be understood that I do not wish to be limited exactly thereto, since various modifications may be made without departure from the scope of the invention as set forth in the appended claims.

I claim:

1. Apparatus of the class described including, in combination, a pair of oppositely disposed cold reducing work rolls between which metallic material is adapted to pass so as to effect a reduction in the thickness thereof, and a longitudinally extending drag shoe made of a fibrous substance arranged substantially parallel to the axes of said rolls on the entrance side thereof and immediately in front of the same, and reciprocable means for moving and supporting said drag shoe, said reciprocable means in one position adapted to project said shoe across the path of the material entering between the rolls so as to force the material into engagement with one of said rolls at a spaced distance from the bite of said rolls whereby that portion of the material between said shoe and the bite of the rolls is placed under tension as the material passes continuously between the rolls.
2. Apparatus of the class described including, in combination, a pair of oppositely disposed cold reducing work rolls between which metallic material is adapted to pass so as to effect a reduction in the thickness thereof, a drag shoe arranged on the entrance side of said work rolls immediately in front thereof at a point to one side of the strip material for pressing said material securely against one of said work rolls while the material is moving between the rolls with the coefficient friction of the drag shoe against the metallic strip being greater than that between the metallic strip and the roll against which the strip is forced by said drag shoe whereby that portion of the strip material between the drag shoe and the bite of said rolls is placed under tension, and means for moving said drag shoe together with the strip material to operative position against that roll and to a retracted position away from said roll.

EARL D. SPANGLER.
